UNITED STATES PATENT OFFICE.

BURT A. PETERSON, OF ROCKFORD, ILLINOIS, ASSIGNOR TO BARBER-COLMAN COMPANY, OF ROCKFORD, ILLINOIS, A CORPORATION OF ILLINOIS.

YARN CLEARER OR THE LIKE.

Application filed January 13, 1923. Serial No. 612,428.

Among the salient objects of this invention are to provide a yarn clearer adapted for use with various types of yarn-winding machinery which shall serve effectively to 5 remove particles of leaf, boll, seed, wild yarn and other extraneous matter from the running thread; which shall prevent the passage of an objectionably large bunch in the thread; which shall perform its functions 10 without subjecting the thread to wear; and which may be easily cleaned when occasion requires.

It will conduce to an understanding of the practical requirements which a yarn 15 clearer must satisfy if some mention be made of the surface characteristics of yarn. In the spinning of yarn and the operation preparatory thereto, the fibres are not perfectly straightened, but, on the contrary, the body 20 of the yarn is surrounded by small closed loops and free ends of fibres projecting in various directions. Yarn, therefore, does not have an even, well-defined peripheral surface. For this reason a yarn clearer must be 25 capable of removing from the yarn pieces of leaf, boll, seed, gouts, and the like, without so engaging the loops on the periphery of the yarn as to cause undesired yarn breakage. The general object of the invention, 30 therefore, is to produce a yarn clearer which shall meet these somewhat conflicting requirements.

In the accompanying drawings, Figure 1 is an illustration of one embodiment of the 35 invention, the view being taken from the right-hand side of Fig. 3. Figure 1^a is a view, more or less diagrammatic, illustrating the yarn clearer, the detector, and a means for winding and rapidly traversing the yarn. Fig. 2 is a vertical sectional view taken in 40 the plane of line 2--2 of Fig. 3. Fig. 3 is a front elevation. Fig. 4 is a plan view of certain thread-guiding means comprised in the device.

The yarn clearer herein shown is especially 45 adapted for use in connection with a winder of the type disclosed in the Colman Patents Nos. 1,267,977 and 1,274,386, granted May 28, 1918, and August 6, 1918, respectively. The winder shown in these patents is provided with bobbin-holders of the side-delivery type wherein the bobbin is revolved as 50 the yarn is unwound. The present yarn clearer is also adapted for use in a winder 55 of the character shown in the Colman Pat-

ent No. 1,311,498, dated July 29, 1919. It may also be used in a winder provided with bobbin-holders of the end-delivery type shown, for example, in my application Serial No. 323,194, filed September 11, 1919, 60 wherein the yarn mass is stationary during the unwinding of the yarn, the yarn being drawn off the upper end of the bobbin. The yarn clearer shown in the present drawings is also adapted for use with various other 65 forms of spoolers and winders.

The yarn clearer herein shown comprises two downwardly converging clearing blades, together with means for guiding a thread T to run upwardly between said blades, the 70 lower edges of the blades being close enough to the path of the thread to intercept matter from which the thread should be freed. The form of thread-guiding means herein shown comprises a lower plate 1 and an upper plate 75 2, these plates being spaced apart in parallel relation by means of an intermediate plate or block 3. The plates 1, 2 and 3 are rigidly secured together and constitute the base of the yarn clearer. The right-hand ends of 80 the plates 1 and 2, as viewed in Fig. 3, project beyond the plate 3. Preferably, the right-hand end of the plate 1 is rounded as indicated in Fig. 4. The lower plate 1 has a rearwardly extending notch or slot 4 formed 85 therein. The right-hand end of the plate 2 is cut away to form a straight thread-guiding edge 5 extending perpendicularly to the direction in which the slot 4 extends, said edge 5 being approximately in the vertical 90 plane of the inner end wall 6 of the slot 4. The edge of the plate 2 forwardly of the thread-guiding edge 5 is rounded, as shown at 7.

A finger 8 extending parallel with the 95 plates 1 and 2 is supported above said plates in such position that the edges 5 and 6 and one side of the pin 8 are approximately in the same plane. One or more pins 9 are arranged above the pin 8 and parallel thereto. The pins 8 and 9 constitute a stationary grid against which the running thread is yieldingly held by one or more detector fingers 10 of the winder mechanism, as shown in Fig. 1. In the construction herein 100 shown, the fingers 8 and 9 are secured to two vertical plates 11 and 12 formed from an integral piece of sheet metal bent to provide the connecting portion 13. The plates 11 and 12 are secured to the base of the yarn 110

clearer by means of two screws 14 extending through the portion 13.

Two blades 15 and 16 are supported at opposite sides of the path of the yarn between the guide edge 5 and the guide finger 8. In the form herein shown, these blades are provided with integral clips or sleeves 17 fitting tightly about two shafts 18 and 19. The portions of said shafts which are surrounded by the sleeves 17 are of substantially rectangular cross section; thus the blades are held against movement with relation to their respective shafts. The shafts 18 and 19 are mounted for rocking movement in the plates 11 and 12, the corners of these shafts being sufficiently rounded to permit the shafts to turn in openings in said plates.

The blades 15 and 16 are yieldingly held with their lower edges close to the path of the thread. Approaching movement of the blades may be limited in any suitable way, as, for example, by means of a stop finger 20, one end of which is mounted for slight rocking movement in an opening 21 (Fig. 3) in the plate 12. The other end of the stop finger 20 extends through a vertically elongated opening 22 (Fig. 1) in the plate 11 into position to be engaged by the lower portions of the blades 15 and 16. The stop finger 20 is held in adjusted position by means comprising, in this instance, a screw 23 seated in the portion 13 and extending freely through an opening in the stop finger 20. A helically coiled expansive spring 24 surrounds the screw 23 and holds the stop finger 20 up against the head of the screw.

The means for yieldingly holding the blades 15 and 16 in contact with the stop finger 20 comprises, in the present embodiment, two leaf springs 25 integrally connected together and supported upon the fingers 9 between the plates 11 and 12. The free ends of the springs 25 bear against levers 26 non-rotatably connected to the shafts 18 and 19. In one of the springs 25 is formed an opening 27 (Fig. 2) to provide access to the screw 23.

The lower edges of the blades 15 and 16 are bevelled and serrated to provide a series of relatively broad but sharp teeth 15^a at each side of the path of the thread. In serrated yarn clearers of the prior art the teeth were relatively fine or slender. Practical experience with yarn clearers embodying such fine-tooth combs has shown that the teeth catch the fine fibres which extend from the yarn and soon clog up. In fact, by thus collecting fibres a fine-tooth comb acts to form gouts and slubs which may later be released and carried along on the yarn. Moreover, if the yarn be not guided so that its tension keeps the body of the yarn away from the teeth, the latter catch the loops

which project from the body of the yarn, the loops sliding up the teeth and thus drawing the running yarn closer and closer to the teeth until the yarn is impaled on one or more teeth and broken. By reference to Fig. 3 it will be observed that the teeth 15^a employed in the present yarn clearer are sufficiently wide so that when a loop catches on a tooth the tooth will expand and break the loop, thus preventing the yarn from becoming engaged with and broken by the tooth. The relative lateral motion between the toothed blade and the yarn also assists to break loops that catch on the teeth. Furthermore, because of the breadth of the teeth the tendency of lint and the like to collect upon and adhere to and between the teeth is reduced to a minimum.

Upon reference to Fig. 1 it will be noted that the running yarn is guided at the points 5 and 6 below the edges of the blades 15 and 16, and is guided by the parts 8 and 10 above said blades. The yarn, therefore, is not positively held away from the teeth. If the fine-tooth combs of the prior art were employed in connection with yarn thus guided, the before-mentioned loops on the periphery of the yarn would catch on the points of the teeth and draw the yarn aside until the yarn became impaled upon a tooth, thereby breaking the yarn. The forward blade 15 is cut away at 28 (Fig. 3) and the shaft 18 is correspondingly shortened so that said shaft and blade shall not project into the path taken by a thread when being placed in the yarn clearer. As shown in Fig. 3, the guide plate 2 projects to the right slightly beyond the ends of the blades 15 and 16 so as to guide the entering thread past the end of the blade 15. After the entering thread has passed the guide surface 7, it springs behind the guide edge 5 and into the space between the blades 15 and 16.

It will be noted that the guide edges 5 and 6 permit the thread to reciprocate laterally as the thread is being drawn upwardly between the blades 15 and 16 due to the rotation of the cam drum CD. For a full disclosure of the cam drum and the manner in which it causes a rapid traverse of the yarn, reference may be had to the Colman Patent No. 1,274,386. The ballooning of the yarn adjacent to the supply bobbin superimposes short rapid reciprocations upon the traverse caused by the cam drum. As will be understood from Figs. 3 and 4, the yarn is free to move laterally in the notch 6 to the extent determined by the width of said notch. The positions between which the yarn T reciprocates are indicated by the dotted lines *a* and *b* in Fig. 3. When the yarn clearer is used in winders where such lateral motion is imparted to the thread, the teeth of the yarn clearer are particularly effective, as the rapid reciprocation of the thread assists

to detach from it anything engaged by the blades 15 and 16.

If desired, means may be provided to swing either or both of the blades 15 and 5 16 away from their normal position. Herein, the shaft 19 is shown as having an angular portion 29 constituting a crank arm for swinging the blade 16. When the yarn clearer is used in an automatic winder, as, 10 for example, in a winder of the type shown in Patent No. 1,267,977, the traveling mechanism of the winder is provided with a cam bar arranged to depress the crank arm 29. The traveling mechanism also comprises 15 means for discharging the spent bobbin from the bobbin-holder. If there be a strand of yarn extending from the spent bobbin up through the yarn clearer such strand is drawn down with the bobbin when the latter is discharged, the strand carrying with it such lint, etc., as may be clinging to the blades 15 and 16.

When the yarn clearer is used in a winder which does not comprise a traveling winder- 25 tending mechanism, the crank arm 29 may be manually operated.

In the following claims, the terms "yarn" and "thread" are intended to include any analogous material.

30 It will be apparent that certain features herein shown are adapted for use in various types of textile apparatus, as, for example, yarn-tensioning devices and yarn guides.

I claim as my invention:

35 1. A yarn clearer having, in combination, plates 11 and 12, parallel rock shafts journaled in said plates and projecting at one side of said plates, yarn-clearing blades on said projecting shaft portions, a stop finger 40 supported at one end in one of said plates and extending through the other plate so as to be movable relative thereto and projecting between said blades, means for holding said stop finger in adjusted position, 45 and means for holding the blades against the stop finger.

2. A yarn clearer having, in combination, a supporting structure, parallel rock shafts journaled in said structure and projecting 50 at one side thereof, yarn-clearing blades on said projecting shaft portions, a stop finger supported by said structure and projecting between said blades, means for holding said stop finger in adjusted position, and means 55 for holding the blades against the stop finger.

3. A yarn clearer having, in combination, a rock shaft, a yarn clearing blade on said shaft, another yarn-clearing blade opposite 60 and close to the first blade, and a crank arm on said shaft for pivotally moving the first blade to swing it laterally toward and from the second blade.

4. A yarn clearer having, in combination, 65 a plate having a slot therein, said slot hav-

ing a rear end wall constituting a guide for a running thread, said wall being sufficiently long to permit lateral motion of the thread, another plate above the first mentioned plate and overlying said slot, the forward 70 side of the second plate being rounded to guide the entering thread into position rearwardly of the second plate, a third guide above the second plate, one side of said third guide, the rear edge of the second plate and the end wall of said slot being approximately 75 in the same plane, and clearing means arranged to act upon the thread at a point between the second plate and the third guide.

5. A device to act upon yarn having, in combination, a plate having a slot therein, said slot having a rear end wall constituting a guide for a running thread, said wall being sufficiently long to permit lateral motion 85 of the thread, another plate above the first mentioned plate and overlying said slot, the forward side of the second plate being rounded to guide the entering thread into position rearwardly of the second plate, a 90 third guide above the second plate, and means arranged to act upon the thread at a point between the second plate and the third guide.

6. A device to act upon yarn having, in combination, a plate having a slot therein, said slot having a rear end wall constituting a guide for a running thread, another plate above the first mentioned plate and overlying 95 said slot, the forward side of the second plate being rounded to guide the entering thread into position rearwardly of the second plate, a third guide above the second plate, and means arranged to act upon the thread at a point between the second plate and the third guide.

7. A yarn clearer having, in combination, a supporting structure, two parallel rock shafts mounted in said structure, a pair of 110 yarn clearing blades mounted on said shafts for relative lateral swinging movement, adjustable means for determining the normal position of said blades, and spring means for holding the blades in such position.

8. A yarn clearer having, in combination, 115 two yarn clearing blades mounted on parallel axes for relative lateral swinging movement, adjustable means for determining the normal position of said blades, and spring means for holding the blades in such position.

9. A yarn clearer having, in combination, two pivoted yarn-clearing blades adapted to swing laterally toward and from each other, an adjustable stop between the blades, and spring means for holding the blades against 120 the stop.

10. A yarn clearer having, in combination, two pivoted yarn clearing blades adapted to swing laterally toward and away from each other, spring means tending to swing said 125

blades toward each other, an adjustable stop between the blades for limiting the movement thereof by said spring means, and manually operable means for swinging the blades 5 against the action of said spring means.

11. A yarn clearer having, in combination, guide means for a running thread, said guide means permitting lateral motion of the thread, and yarn-clearing blades located 10 close to and at the opposite sides of the path of the thread with their flat faces in opposed relation, one of said blades being pivotally movable into and out of operative position.

12. A device of the character described 15 comprising, in combination, a rock shaft, a yarn clearing blade on said shaft, a second yarn clearing blade opposite and close to the first blade, spring means tending to move the first blade toward the second blade, and 20 adjustable means for determining the normal relative positions of said blades.

13. A device of the character described 25 comprising a supporting structure, a pair of rock shafts mounted in said supporting structure in parallel relation, a pair of yarn clearing blades mounted on the respective shafts at opposite sides of the path of the thread, a pair of leaf springs adjacent each of said shafts and mounted in the supporting structure, and levers on said shafts arranged to be engaged by said leaf springs whereby the latter serve to hold the blades 30 in operative position.

14. A device of the character described 35 comprising, in combination, a pair of rock shafts mounted to turn on parallel axes, a yarn clearing blade carried by each of said shafts, a lever on each of said shafts, and spring means acting upon each of said levers whereby to rock said shafts in opposite directions.

15. A device of the character described 45 comprising, a pair of rock shafts mounted on parallel axes and each having a yarn clearing blade thereon, spring means acting to turn said shafts in opposite directions whereby to move said blades together, and adjustable means for determining the relative positions of said blades.

16. A device of the character described 50 comprising guides for a running thread, a pair of shafts mounted to turn on parallel axes and spaced a substantial distance on opposite sides of the path of the running thread, a pair of yarn clearing blades carried by the respective shafts and depending therefrom downwardly and inwardly toward each other, means operating to move

said blades together, and means located between the blades near their lower ends to 60 hold them in properly spaced relation.

17. A device of the character described comprising, in combination, guide means for a running thread, yarn clearing means located between the guide means and including a pair of blades mounted in opposed relation and respectively having portions inclined toward each other, and a stop finger with which such inclined portions of the blades engage to determine their relative positions.

18. In a winder in which the yarn is rapidly traversed, in combination, guide means for the running yarn adapted to permit lateral motion of the yarn, and a yarn clearer located between said guide means and including a pair of toothed blades mounted at opposite sides of the path of the rapidly traversed yarn, said blades providing opposed toothed surfaces between 80 which the yarn passes so as to be cleared thereby, said guide means permitting rapid traverse of the yarn, the teeth of said blades being relatively broad so as to reduce to a minimum the collection of lint and fiber, 85 and break any peripheral loops on the yarn which the teeth may enter.

19. A winder having, in combination, a serrated member close to the path of the yarn, means for causing relatively rapid traversing movement between said serrated member and the yarn, and yarn guide means which will permit such rapid traverse, the teeth of said member being relatively broad so as to reduce to a minimum the collection 95 of lint and fiber, and break any peripheral loops on the yarn which the teeth may enter.

20. A yarn-guiding structure having, in combination, a member having a notch therein in which the yarn may have limited lateral movement, the rear wall of said notch constituting a guide for the yarn, another member above the first mentioned member and overlying said notch, one side of the 105 second member being rounded to guide the entering thread into position rearwardly of the second member, and a third guide above the second member, one side of the third guide, the rear edge of the second member and the rear wall of said notch being approximately in the same plane.

In testimony whereof I have hereunto affixed my signature.

BURT A. PETERSON.
